US00D769857S

(12) **United States Design Patent** (10) **Patent No.:** **US D769,857 S**
(45) **Date of Patent:** **** Oct. 25, 2016**

(54) **COVER WITH DISPLAY FOR MOBILE COMMUNICATIONS DEVICE**

(71) Applicant: **SAMSUNG ELECTRONICS CO., LTD.**, Suwon-si, Gyeonggi-do (KR)

(72) Inventors: **Changbong Shin**, Suwonsi (KR); **SungJin Park**, Seoul (KR); **JongIn Lee**, Suwonsi (KR)

(73) Assignee: **SAMSUNG ELECTRONICS CO., LTD.**, Suwon-Si, Gyeonggi-Do (KR)

(**) Term: **15 Years**

(21) Appl. No.: **29/543,539**

(22) Filed: **Oct. 26, 2015**

Related U.S. Application Data

(62) Division of application No. 29/468,248, filed on Sep. 27, 2013, now Pat. No. Des. 754,643.

(57) **CLAIM**

The ornamental design for a cover with display for mobile communications device, as shown and described.

DESCRIPTION

FIG. 1 is a front perspective view of a cover with display for mobile communications device showing our new design; FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a front perspective view of the cover with display for mobile communications device shown in an example environment;

FIG. 10 is a front view of the cover with display for mobile communications device shown in an example environment;

FIG. 11 is a front perspective view of another embodiment of a cover with display for mobile communications device showing our new design;

FIG. 12 is a front view thereof;

FIG. 13 is a rear view thereof;

FIG. 14 is a left-side view thereof;

FIG. 15 is a right-side view thereof;

FIG. 16 is a top view thereof;

FIG. 17 is a bottom view thereof;

FIG. 18 is a rear perspective view thereof;

FIG. 19 is a front perspective view of the cover with display for mobile communications device shown in an example environment; and,

FIG. 20 is a front view of the cover with display for mobile communications device shown in an example environment. The broken lines depict environmental structure that forms no part of the claimed design.

1 Claim, 20 Drawing Sheets
